(57) **CLAIM**

The ornamental design for a pipe stand, as shown and described.

DESCRIPTION

FIG. 1 is a front perspective view of a pipe stand;
 FIG. 2 is a top view of the pipe stand;
 FIG. 3 is a bottom view of the pipe stand;
 FIG. 4 is a front view of the pipe stand, the rear view being a mirror image thereof;
 FIG. 5 is a right side view of the pipe stand, the left side view being a mirror image thereof; and,
 FIG. 6 is a rear perspective view of the pipe stand.
 The broken lines depict portions of the structure that forms no part of the claim.
